UNITED STATES - PATENT OFFICE.

JOHN R. MASECAR, OF TORONTO JUNCTION, CANADA, ASSIGNOR OF ONE-HALF TO DAVID BROWN, OF DONAGHMORE, IRELAND.

SOAP-PRESS.

SPECIFICATION forming part of Letters Patent No. 699,887, dated May 13, 1902.

Application filed December 11, 1901. Serial No. 85,472. (No model.)

To all whom it may concern:

Be it known that I, JOHN R. MASECAR, a subject of the King of Great Britain, residing at Toronto Junction, in the county of York, 5 in the Province of Ontario, Canada, have invented certain new and useful Improvements in Presses for Soap or other Plastic Material, of which the following is a specification.

My invention relates to machinery for press- 10 ing or stamping bars or cakes of plastic material, such as soap, and has for its object to provide an improved machine by which the bars may be rapidly and automatically fed into the dies one after another, stamped, and 15 discharged from the machine without requiring manipulation by the attendant beyond the simple placing of said bars in the receiving-conveyer.

It has been proposed heretofore to construct 20 automatic soap-presses with a charging table or guideway onto which the bars to be pressed were fed through a vertical or inclined chute opening at the bottom upon said guideway, a plunger being arranged to slide to and fro in 25 the guideway to push the bars of soap placed therein into the dies. A discharge track or conduit was provided on the opposite side of the dies from the charging-guideway in alignment therewith, and each unpressed bar as it 30 was fed forward was intended to dislodge from the dies the bar already pressed and push such pressed bar ahead of it onto the discharge-track. This machine is open to objection in that the bars of soap are apt to be 35 mutilated and stuck together when the unpressed bar is pushed violently against the one which has been pressed and is sticking to the die, and it would also sometimes happen that the pressed bar would not be moved 40 completely out from between the dies, so that one edge thereof was caught between them and mutilated.

In accordance with my invention a dis- 45 charging-striker is combined with the charging device and arranged to act at an angle thereto to strike the pressed bar which may be sticking the die, dislodge said bar, and throw the same out of the path of the oncoming unpressed bar before the latter reaches 50 the dies. A stop may be provided on the opposite side of the dies from the charging de-

vice, so that the unpressed bars may be arrested at the proper point immediately between the dies, and a discharge track or guideway leading to a traveling conveyer 55 may be provided to receive the pressed bars as they are thrown out of the dies.

A further feature of the invention consists in providing a yielding spring connection between the lever which actuates the movable 60 die and the pitman or part by which such lever is moved, so that the movement of the die may be accommodated to some extent to the thickness of the cake which is being pressed. 65

In the accompanying drawings I have illustrated my invention as applied to a soap-press of well-known form which was originally designed to be fed by hand and operated by foot-power, this press having been converted 70 by means of my invention into an automatic press.

Figure 1 is a plan view of the machine. Fig. 2 is a side elevation thereof. Fig. 3 is a detail of a portion of the mechanism. Fig. 4 is 75 a front or end view; and Fig. 5 is a detail sectional view on line 5 5, Fig. 2.

Similar letters of reference are used to designate the same parts wherever they are 80 shown.

The machine illustrated embodies besides the improvements of my invention certain other improvements which were invented jointly by myself and Thomas Bevington, and which are described and claimed in a separate 85 application, Serial No. 85,473, filed December 11, 1901.

The upper and lower dies *a a* are arranged to reciprocate in vertical planes in a well-known manner, the upper die being attached 90 to a sliding cross-head *c* and the lower die being arranged to slide vertically in the die-box *a'*, said lower die being yieldingly maintained in an elevated position at the top of the die-box through the agency of a spring *c'* in a 95 well-known manner. I have shown a vertical rod *t*, carrying at its upper and lower ends, respectively, arms *t' t'*. The arm *t'* supports the lower die, and the arm *t'* extends over the sliding cross-head *c*, so that as said cross-head 100 is raised after a cake is stamped it strikes the arm *t'* and so positively raises the lower die

by raising the rod t and the arm t' , which support said lower die. The spring c' is confined between the frame of the machine and a collar on said rod t to yieldingly maintain the rod 5 in an elevated position. This structure is known in the art and requires no further description. The cross-head carrying the upper die is reciprocated by means of a bell-crank lever d , pivoted at d' to the frame of the machine. The lower end of the lever d , which in the machine illustrated was originally intended to be moved by the foot of the operator, is connected by means of a pitman-rod e with a crank-pin f^4 , which is carried by a 10 crank-disk f , mounted on the main driving-shaft f' . The shaft f' is rotated by the main driving-belt wheel f^2 , with which it is connected through suitable clutch mechanism f^3 . The pitman e is not rigidly connected to the 15 lever d , but is arranged to slide in the yoke-piece e' , which embraces the lower end of the lever and is pivoted thereto. A collar e^2 , arranged to slide in the manner of a cross-head along the arms of the yoke-piece e' , is fixed 20 rigidly upon the inner end of the pitman-rod e , and a strong compression-spring e^3 , encircling the rod, is confined between the sliding collar and the cross-bar of the yoke-piece. When a soap bar of unusual thickness is 25 placed between the dies, the upper die cannot descend as far as it ordinarily would, and the yielding spring connection between the pitman and the operating-lever makes the machine automatically adjustable to stamp soap bars of varying thickness. When the upper die has descended as far as it will go by reason of the thickness of the soap bar, any 30 farther outward movement of the pitman in a direction to depress the die still farther is taken up by the sliding of the pitman-rod within the yoke-piece e' against the tension of the spring e^3 . A charging table or guideway g is provided at the front of the machine, leading to the open mouth of the 35 die-box, and a reciprocating plunger g' is arranged to slide to and fro in said guideway, so that when a bar of soap is placed in the guideway said plunger will serve to push the soap along the table and into the dies, where 40 it is stamped. To actuate the charging-plunger g' , a centrally-pivoted oscillating-lever h is provided, the upper end of said lever being connected to the plunger and the lower end thereof being slotted to engage a pin h' , which 45 is carried by a rotating crank-disk h^2 . The crank-disk is mounted on a counter-shaft h^3 , which is connected through suitable bevel-gearing and an intermediate shaft k with the main driving-shaft f' . To expel the stamped 50 bars from the dies, I have provided a discharging-striker, which may be a reciprocating plunger l , sliding in a suitable guideway, and which, acting in a plane at right angles to the plunger g' , throws the stamped bars 55 laterally out of the dies and onto the discharge track or guideway m . A conveyer n may be arranged to receive the bars as they

are ejected through the discharge-guideway. One wall m' of the guideway m is extended angularly over the conveyer n , so that the 70 stamped bars passing from the discharge-track m onto the conveyer will be arrested by said extension m' , so that their momentum will not carry them clear off the conveyer and to carry said bars to the wrapping-tables. 75 The plunger l is reciprocated by means of a centrally-pivoted oscillating lever l' , the upper end of which passes through a hole in the plunger and the lower end of which is adapted to be engaged by a pin l^2 , carried by the 80 rotating disk l^3 , mounted on the shaft k . At each rotation of the disk the pin l^2 strikes the lower end of the lever, which is interposed in its path, and moves said lever in a direction to advance the discharge-plunger. 85 As soon as the pin passes the end of the lever the plunger l is instantly snapped back by means of a spring. In the machine illustrated the spring which retracts the discharging-plunger is an elastic bar of wood o , anchored 90 at the bottom to the frame of the machine and having its free end connected to the rear end of the plunger l by a rope or thong o' . A considerable advantage is obtained by quickly snapping back the discharge-plunger the instant after it reaches the end of its stroke 95 instead of having it moved back at the same speed at which it was advanced. An unpressed cake cannot be pushed between the dies until the discharge-plunger is out of the 100 way, and the work of that plunger is done the moment the pressed cake is thrown into the discharge-track, so that the quick return of the plunger makes possible a considerable increase in the operative speed of the ma- 105 chine.

One wall of the guideway in which the discharge-plungers slides is extended past the die-box to face the charging-plunger, forming a stop which serves to arrest the oncoming unpressed cakes at the proper point immediately between the dies. 110

It is understood, of course, that the mechanism for moving the die and the charging and discharging plungers is adjusted so that the 115 several movements will be properly timed, the charging-plunger being advanced just before the descent of the die and the discharging-plunger advanced, so as to strike the pressed cake the instant after the dies have 120 released it.

Any desired means may be provided for feeding the cakes to the charging-table. I have shown a feeding box or chute p extending diagonally upward from the side of the 125 charging-table, said chute being adapted to receive the soap bars end to end and feed them laterally onto the charging-table into the path of the charging-plunger. When the charging-plunger moves forward, it pushes 130 the bar of soap from the charging-table on into the dies to be stamped, one edge of said plunger serving meanwhile to support the column of bars in the feed-box. As the charg-

ing-plunger is retracted after each forward movement, the bar of soap at the bottom of the feeding-chute slides onto the charging-table and all the other bars move down one 5 step in the chute. To feed the soap bars into the chute *p*, I have shown two conveyers *q r*, one of which receives the cakes placed thereon in a row by the attendant and the other of said conveyers arranged in a lower plane 10 than the first receives the cakes as they fall one by one from the end of the main conveyer and transfers said cakes to the feeding-chute, the cakes being turned on their sides in passing from the first-mentioned conveyer to the 15 second. All that is necessary for the attendant to do is to place a row of soap bars to be pressed upon the main conveyer. The bars are then automatically carried one by one to the charging-table, pushed between the dies, 20 stamped, and finally ejected laterally from the machine onto the conveyer-belt *n*, which carries them to the wrapping-tables.

I have shown means for moistening the cakes of soap as they slide through the feeding-chute *p* onto the charging-table, said means consisting of a flap of cloth *s²*, which rests upon the soap cakes, as shown most clearly in Figs. 4 and 5, said flap being directly below the spigot *s'* of a water-jug *s*, 30 from which the water slowly drips onto the cloth.

It is evident that the ideas herein set forth may be embodied in machines which may differ in details from the one shown in the 35 drawings. I do not, therefore, desire to be limited to the precise structure illustrated; but,

Having described one form of my invention, I claim—

40 1. In a machine of the class described, the combination with the vertically-reciprocating dies, of a charging-table, a charger arranged to push the bars placed thereon into the dies, and a discharging-striker acting in the plane 45 of the charger at an angle to the line of movement thereof adapted to dislodge the pressed bar from the dies and throw the same laterally out of the path of the unpressed bar which is to be advanced by the charger, sub- 50 stantially as set forth.

2. In a machine of the class described, the combination with a die-box having a mouth or opening at the top, of the vertically-recip-

rocating upper die adapted to force a cake to be pressed down into a die-box through said opening, the lower die reciprocating vertically within the die-box and arranged to return the stamped cake to the mouth of the box, a charging-table on a level with the mouth of the die-box, a charger arranged to 55 push an unstamped cake along said table to the mouth of the die-box, a discharge-track leading laterally from said mouth of the die-box, the discharging-striker arranged opposite said discharge-track facing the same and 60 acting across the mouth of the die-box to throw the pressed cakes into the discharge-track, and mechanism for automatically actuating the several moving parts, as set forth.

3. In a machine of the class described, the combination with the vertically-reciprocating dies, of a charging-table in front of said dies, a charger adapted to push between the dies a bar or cake placed on said charging-table, a discharging-striker acting at an angle to 70 the charger in the same horizontal plane to dislodge the pressed bar from the dies and throw the same laterally out of the path of the unpressed bar which is to be advanced by the charger, and mechanism for actuating 75 the striker, said mechanism being arranged to retract the striker more quickly than the same is advanced.

4. In a machine of the class described, the combination with the vertically-reciprocating dies, of a charging-table in front of said dies, a reciprocating charging-plunger arranged to slide to and fro on said table, and mechanism for actuating said plunger, a discharge-track at right angles to the line of travel of 80 the charging-plunger, a stop on the opposite side of the dies from the charging-plunger, a discharging-plunger arranged to slide to and fro in a path at right angles to the charging-plunger and facing the discharge-track, mechanism for advancing the discharge-plunger, and a spring for quickly snapping back the 85 said discharge-plunger after it has made its forward journey.

In witness whereof I have hereunto set my 90 hand this 23d day of November, 1901.

JOHN R. MASECAR.
